UNITED STATES PATENT OFFICE.

JOHN J. LYTH, OF VALLEYFIELD, QUEBEC, CANADA.

CLOTH-PILEING MACHINE.

Application filed July 25, 1925, Serial No. 46,123, and in Canada June 12, 1924.

This invention relates broadly to improvements in apparatus for piling roped cloth in circular kiers and the like, and especially to improvements in the form of apparatus shown in my former Patent No. 1,528,065, granted the 3rd March, 1925.

The primary object of the present invention is to provide a mechanism for accomplishing the objects of the original invention, the said mechanism being of design superior to that formerly disclosed and capable of operating with great steadiness, regularity and accuracy and of delivering the cloth with precision along a predetermined path.

A further object is to provide means for piling the cloth in kiers and the like and simultaneously impregnating the cloth with either hot or cold bleaching liquors, whereby uniformity of impregnation may be obtained, kier stains avoided in bleaching and a great saving of time effected by eliminating the delay usually necessary for the liquors to penetrate the mass of piled cloth, and also to raise the mass to cooking temperature and in addition to enable a dense piling to be effected by reason of the cloth being weighted with liquid.

Another object is to provide a mechanism capable of dealing with two or more ends of cloth simultaneously, whereby the yardage of cloth piled per unit of time may be still further increased.

Still another object is to provide mechanism enabling a kier to be filled substantially to its top.

Various additional objects and the advantages of the invention may be ascertained from the following description and the accompanying drawings.

In the accompanying drawings illustrating one embodiment of the improvements now sought to be patented:—

Fig. 1 is a side elevation of the apparatus illustrating in full lines the position of the conduit for passage through a kier mouth, and in broken lines the position of the conduit when piling cloth at the wall of a kier.

Fig. 2 is a fragmentary plan view of the truck supporting the piling mechanism.

Fig. 3 is a vertical sectional view at the centre of the piling mechanism proper.

Fig. 4 is a fragmentary sectional view on

an enlarged scale illustrating the detail at the right hand lower corner of Figure 3. 55

Fig. 5 is a plan view of the piling mechanism, the hood and cloth conduit being removed.

Fig. 6 is a side elevation of the lower part of the conduit in fully extended position. 60

Fig. 7 is a fragmentary elevation of the conduit viewed at right angles to the plane of section of Figure 3 and the plane of Figure 6, and illustrating the manner of supporting the intermediate part of the conduit 65 and other details.

Fig. 8 is a cross sectional view on the line 8—8, Figure 6.

Fig. 9 is a vertical sectional view of the upper end of the conduit broken away from 70 Figure 3.

Referring more particularly to the drawings, 11 designates a kier or the like and 12 an overhead track upon which is mounted a carriage comprising side sills 13 connected 75 by transoms 14 and provided with rotatably mounted axles 15, on the ends of which are flanged wheels 16 rotatable relatively to the axles and running on the track 12. Wind- 80 ing drums 17 are fixedly mounted on the axles adjacent the ends thereof and, in addition, on each axle there is fixedly mounted a worm wheel 18. A shaft 19 is mounted longitudinally of the truck between the side sills thereof in the plane of the worm wheels 85 18 and is journalled in bearings 20 depending from the transoms. This shaft carries worms 21 meshing with the worm wheels 18 of the axles. The shaft 19 is additionally provided with a chain wheel 22 and endless 90 chain 23 or other convenient means by which it may be rotated in either direction. Cables or the like 24 are connected to the drums 17 and serve to suspend the piling 95 mechanism from the carriage. By pulling on the chain 23, the shaft 19 may be rotated to rotate the axles and drums to wind up or let out cables for the purpose of rais- 100 ing or lowering the piler. As the running wheels are loosely mounted on the axles, the axles may be rotated within the wheels without causing movement of the carriage along the track. When it is desired to shift the piler to or away from the kier, the truck is drawn or pushed along the track. In this 105 travel of the truck, the running wheels ro-

tate on the axles which are locked against revolution by the worm gearing, so that there is no possibility of axle rotation which would cause raising or lowering of the piler during its transportation. If desired, brakes may be applied to the running wheels to prevent truck creepage during raising or lowering of the piler, but ordinarily, this will not be required. Obviously, the drums 17 and worm wheels may be connected otherwise than through the axles, and it will therefore be understood that the construction herein described may be varied in detail without departing from the spirit of the invention. The kier 11 may constitute one of a series of similar kiers or other containers arranged in a row, and in such case the track 12 will extend over the row so that the piler may be transported from one container to the other of the row.

The piling mechanism is contained within and supported by an annular frame 25, which may be regarded as stationary in so far as the elements of the piling mechanism are concerned. This frame is provided with externally projecting lugs or brackets 26, to which the supporting cables 24 are connected. A frusto-conical, centrally apertured cover 27 is removably mounted on the frame 25 to protect the piling mechanism within the frame from droppings of bleach liquor or other corrosive liquid. The lower edge of the frame is inwardly turned a short distance to provide a raised seat or bearing face 28, and also an upstanding flange 29 at the inner edge of the seat, which flange is outwardly sloping in its upper part, as at 30 and shown most clearly in Figure 4. The lower edge of the frame is preferably provided with a plurality of radially disposed ribs 31 adapted to rest on the rim of a kier mouth and support the mechanism thereon solidly and without any tendency to rock or creep, such as might be experienced with two plain surfaces if there was any unevenness or foreign matter between them.

A circular plate 32 is provided to fit within the bottom of the frame and to rest upon the seat 28. The lower surface of this plate is provided with an annular groove 33 in which the flange 30 is received and with which the outer wall of the groove is in bearing contact. The groove is somewhat deeper than the flange, whereby the upper part of the groove is unoccupied and constitutes an annular channel above the flange 29. By reason of the seat 28 the plate is rotatably supported and is maintained in rotation about a fixed centre, which is the centre of the casing, by its engagement with the flange 29. The seating portion of the plate is provided with an annular downwardly opening annular groove 34 adapted to hold lubricant and distribute the same inwardly and outwardly on the seat 28. A short distance

above the groove 34, the plate is provided with a second but upwardly opening groove 35 into which lubricant may be delivered from a reservoir 36 mounted exteriorly of the casing. At suitable intervals around the plate, passages 37 are provided leading from the upper groove 35 to the lower groove 34 for the transfer of lubricant from the upper to the lower groove. The tendency of lubricant is always to work out from between the lubricated surfaces and therefor the lubricant will work up between the flange 29 and plate groove wall and would in course of time fill the annular channel 33 and overflow, so as to drop into the kier. This contingency is avoided by the provision, at suitable intervals around the plate, of ducts or passages 38 between the passages 37 and leading outwardly from the channel 33 to the periphery of the plate, so as to discharge any accumulation of oil outwardly of the flange 29 and raised seat. Any accumulation of oil may be drawn off from the frame or casing from time to time by removal of the screw plug 39.

Above the groove 35 the plate is provided with gear teeth 40 to mesh with a worm 41 fixedly mounted on a shaft 42 journaled in a housing 43 attached to the frame. One end of the shaft 42 is provided with a pulley or the like 44, by means of which the shaft may be rotated through a belt drive 45, or other suitable means, from a motor 46 mounted on the frame exteriorly thereof. The rotatable plate 32 carries the cloth conduit and all mechanism for operating the same, and as the plate rotates within the frame or casing it carries the conduit and operating mechanism with it.

The cloth conduit comprises an upper section 47 disposed externally of the cover 27; an intermediate inclined section 48 extending from the central opening of the cover to the plate 32 at a point eccentric thereof; a second intermediate section 49 vertically disposed and rotatably mounted in the plate, and an inclined lower section 50 rigidly connected to the vertical section. The length of the inclined lower section is approximately twice the distance between the axis of the vertical section and the centre of revolution thereof, as shown in full lines, Figure 1, so as to permit of its insertion through the kier mouth and may, by rotation of the vertical conduit section, be swung outwardly of the kier mouth, so that its ends will be in close proximity to the kier wall. The upper section 47 and inclined section 48 are connected by an elbow 51 and the inclined section 48 and vertical section 49 are connected by an elbow 52, while the vertical section 49 and the lower inclined section are connected by an elbow 53. A post 54 is secured to the plate at a point diametrically opposite the vertical conduit section and has secured

thereto, by a clevis 55, an inclined brace 56 which is preferably adjustable as to length and extends from the clevis 55 to a lug 57 on the elbow 51, to which lug the brace is attached. This brace serves to support the upper end of the inclined portion 48 and part of the weight of the upper section 47. The elbow 52 is provided with lugs 58 which extend outwardly over the top of the section 49 and are rigidly connected to the plate 32. The triangular structure of the brace and conduit section 48 is steadied against swaying laterally of the plate containing it by the lugs 58 and by the cover 27. The lugs 58 serve also to keep the weight of the sections 47 and 48 off the vertical section 49.

The upper section 47 of the conduit preferably tapers slightly from its upper end to its lower end and is provided at its upper end with a reinforcing ring 59, upon which is mounted a hollow ring or annulus 60 having an inwardly projecting lower surface 61 provided with a plurality of openings 62 communicating with the interior of the ring and preferably directed to a point on the axis of the section some distance below the ring. The ring 60 is retained by a depending flange 63, which has a running fit with in the ring 59. The ring 60 and the section 47 are relatively rotatable. An inlet 64 is provided for the ring 60, to which inlet may be connected a flexible conduit 65 to deliver a fluid, such as bleach liquor, to the ring. The taper of the section 47 permits the central opening of the annulus 60 at the upper or larger end of the section to be at least as large in diameter and preferably larger than the lower opening of the section. The lower end of the section is provided with a reinforcing ring 66 screw-threaded or otherwise formed for releasable attachment to the upper end of the elbow 51, which projects through the central opening of the cover 27. A cape or water shed 67 in the form of a downwardly curved ring is caught between the reinforcing ring 66 and the elbow and overlies the upper edge of the cover 27, so that any bleaching or other liquid which may run down the outer surface of the section 47 will be directed to the outer surface of the cover and prevented against entry into the piling mechanism between the cover and elbow 51.

The inclined intermediate section 48 is, as will be readily seen, merely a cylindrical tube connected between the elbows 51 and 52.

The vertical intermediate section 49 comprises in its upper part a ring 68, the upper end of which is provided with a pinion 69 for rotating the section, which pinion may conveniently be an integral, outwardly projecting, toothed flange. The lower end of the elbow 52 projects into the ring 68 and the ring has a smooth running fit thereon. Preferably the ring 68 is inwardly flanged

at 70 to provide a seat for the elbow and if desired the elbow may be provided with an external flange bearing on the upper end of the member 68. The lower end of the member 68 is externally taper-threaded and is cut in the threaded portion into a plurality of tongues 71 embraced by a nut 72 on the threaded portion. At one point in the circumference of the threaded portion two of the adjacent tongues are separated by a comparatively wide slot 73. The lower portion of the vertical section is composed of a tube 74 entering the lower part of the member 68 and retained by screwing the nut 72 up over the tapered thread to contract the fingers 71 around the tube. This arrangement constitutes a chuck. The tube 74 may be provided at one point in its circumference with an outwardly extending pin or lug 73a adapted to enter the slot 73 to positively hold the tube against rotation within the member 68. The upper end of the tube 74 preferably seats against the lower surface of the flange 70 so as to present a smooth bore unbroken by inwardly projecting edges on which cloth might catch. The entire section 49 is rotatably mounted in the plate 32 by means of a ball bearing 75, which also sustains the weight of the vertical section and the lower inclined section connected to it.

The lower inclined section 50 comprises a cylindrical tube 76 rigidly connected at one end to the elbow 53 and at the opposite end cut away below its horizontal diameter for a suitable distance, as shown at 77, Figures 1 and 6. A trough or chute 78, semi-circular in cross section, is slidably mounted upon the tube 76 so as to replace when necessary the cut-away portion of the tube or to be drawn up on the tube. This chute is supported by means of rollers 79 connected thereto and running on rails 80 extending substantially the full length of the tube 76 above its horizontal diameter.

A spider 81 is mounted on the lower surface of the plate 32 adjacent the vertical conduit section 49 and carries a stiff depending post 82, to the lower end of which an arm 83 is connected with means for vertical adjustment and removal over the lower end of the post. The free extremity of this arm is bored to receive a steady pin 84 adjustably mounted in a lug 85 depending from the elbow 53, the pin being disposed co-axially with the vertical conduit section 49. This steady pin serves to hold the vertical section 49 against displacement from its vertical position by the weight of the laterally extending lower section 50 and serves also to relieve the ball bearing 75 of unequal loading. If the pin 84 becomes worn, it may be readily replaced without disturbing any of the adjustments of the conduit. The steady arm 83 should be adjusted so as to be out of contact with the lug 85, as it is not desirable

that any of the weight of the conduit should be carried on the arm 83.

The upper edge of the frame 25 is provided with a series of inwardly projecting gear teeth forming a circular rack or internal gear 86. The rack may be separate from the casing or integral therewith, as shown, but in any case a stationary internal gear is provided. A pinion 87 is mounted axially vertical on the plate 32 and meshes with the internal gear 86, so that as the plate 32 is rotated by the worm 41 the pinion 87 will travel around the internal gear and be thereby rotated. The pinion 87 is connected by mitre gears or other suitable means 88 with a horizontal shaft 89 mounted in bearings 90 on the plate. A pair of vertical posts 91 are rigidly secured to the plate 32 and rotatably support a pair of worm wheels 92, each of which meshes with a worm 93 mounted on the shaft 89. The hubs of the worm wheels carry above the wheels, flanges 94 to which complementary cams 95 and 96 are removably and adjustably secured. A circularly curved rack or quadrant 97 is provided to mesh with the rotating pinion 69 of the vertical conduit section 49 and is supported by an arm 98 rotatably mounted on the post 54 below the clevis 55. This quadrant arm 98 lies above the cams and carries on its lower surface a rotatably mounted roller or tracer wheel 99 engaged between the cams.

The profiles or outlines of the cams are such that the roller 99 is not allowed any free play but is constantly in engagement with both cams, each cam serving to hold the roller against the other cam. The outline of the cams is specially designed to cause the arm to oscillate at a varying speed. To enable this, the profile of one cam (96) retreats rapidly from the point of maximum radius, as at 100, so that for a small angular movement of the cam the arm will receive considerable oscillatory movement. As this point of rapid recession starts from the maximum radius of the cam it follows that the rapid movement of the arm will take place immediately after or before change of direction in the oscillation of the arm; in the arrangement shown, immediately after such change of direction. The profile of the cam from the rapid recession to the point of minimum radius of the cam is a smooth curve, so that the remainder of the oscillation of the arm in one direction will be at a substantially uniform speed. On the other side of the long diameter of the cam the curvature is smooth between the points of minimum and maximum radius, so that the arm will be caused to travel at a substantially uniform speed. The profile of the cam 95 is such as to cause the roller to follow the shaft rotation 100 of the cam 96. In other words, while the roller is following the sharply receding

side of the cam 96, the cam 95 is the driving cam; while when the roller is following the opposite side of the cam 96, this cam is driving and the cam 95 serves merely to hold the roller against movement away from the cam 96. The worms 93 are shown as right and left hand, so that the cams will rotate in opposite directions. This arrangement is not essential, as both worms may be pitched in the same direction and the same result obtained by inverting one of the cams.

The oscillatory movement imparted to the arm 98 and the length of the rack 97 bear such relation to the pinion 69 that the same is rotated alternately in opposite directions 80 through an angle of approximately 180°, so that the lower inclined section of the conduit may be swung from a position diametrically under the plate 32 to a position extending radially therebeyond, as shown in Figure 1. The adjustment of the parts is such that the greatest speed of arm oscillation, and therefore of rotation of the vertical conduit section 49, occurs when the lower inclined section commences to swing from 90 its inner position to its outer position.

A semi-circular rack 101 is fixed to the lower side of the plate 32 concentric with the conduit section 49. The upper portion 68 of this conduit section carries a rotatable pinion 102 meshing with the rack 101. A sprocket 103 is rigidly connected with the pinion 102 and a second sprocket wheel 104 is rotatably mounted at the extreme outer end of the inclined conduit section 50. An endless chain 105 passes over the sprockets 103 and 104, being guided around the bend of the elbow 53 by idler rolls 106 rotatably mounted on the elbow and positioned to ensure the lower half of the chain on the inclined section travelling parallel with the axis of the section. A lug 107 is mounted on the trough or chute 78 to engage in the chain and impart movement of the chain to the chute to reciprocate the same upon the lower inclined section as the same swings from its inner to its outer positions. The speed of movement of the chute will have the same characteristic variations as the speed of rotation of the vertical conduit section 49, since it derives its movement from the rotation of the conduit section carrying the pinion 102 around the rack 101.

In order that the operator may know the position of the lower conduit section before attempting to raise the pile off a kier, an alarm device is provided comprising a cam 108 adjustably mounted on the hub of one of the worm wheels 92 and cooperating with a tooth 109 on a pivoted hammer 110. A spring 111 is arranged to hold the hammer against the cam and urge the same toward a gong 112 mounted on the plate 32. The cam 108 is positioned in such relation to the lower conduit section that each time the con-

duit section is swung fully under the plate the cam will release the hammer to be thrown against the gong by its spring 111.

The operation of the piling mechanism is as follows;—The lower section of the conduit being disposed diametrically under the frame as shown in full lines Figure 1, the device is lowered onto a kier mouth and rests securely thereon by reason of the ribs 31 concentrating the load and avoiding creepage. If the upper section 47 of the conduit has been removed owing to lack of head room between the kier and track 12, this section is set and secured in place. The flushing ring 60 is then set on the top of the conduit section 47. One or more ends of cloth in rope form is or are fed into the upper end of the conduit and through the various sections thereof until the end emerges from the lower section and depends from the lower end of the trough or chute 78 into the kier. It will be seen that the cloth depends adjacent but not quite at the central axis of the kier. Threading of the cloth through the conduit may be facilitated by establishing a stream of water or other liquid through the conduit. When the piling is commenced the cloth is fed to the conduit at high lineal speed by means of a wince or other suitable apparatus. Water or preferably bleach liquid or other liquid with which it is desired to impregnate the cloth is supplied through the pipe 65 to the hollow ring 60 and escapes from the ring in a plurality of jets or streams directed downwardly and toward the axis of the upper conduit section 47. These streams of liquid impinge on the cloth in the upper section and thoroughly saturate the same so that the cloth is loaded to many times its natural weight, and by reason of this loading and by reason of the lubrication resulting from unobstructed liquid flow through the conduit the cloth passes through the conduit at high lineal speed. The weight of saturated cloth hanging from the lower end of the conduit will also serve to draw the cloth through the conduit. Theoretically, the cloth will pass through the conduit at approximately the same speed that the liquid flows through. While it may in some instances be preferable, it is not ordinarily essential to supply the liquid under any pressure greater than that necessary to ensure its delivery into the conduit, and it will therefore be understood that the invention is not limited to the means for delivering the liquid in a multiplicity of jets, as in many instances the delivery of a single stream into the upper end of the conduit will suffice to transport and lubricate the cloth and also to impregnate the same. As it is not necessary for the cloth to be touched by operators during the piling and is in fact completely guarded from such handling, it is possible to employ liquid

heated nearly to the boiling point. Any desired excess of liquid over that necessary for complete saturation of the cloth may be used up to the capacity of the conduit and any excess of liquid accumulating in the kier may be drawn off in the usual and well known manner.

Before or as soon as the cloth starts feeding through the conduit, the motor 46 is started to rotate the worm 41 which drives the plate or worm gear 32. This plate carries the entire conduit and because of the rotation of the plate, the upper vertical section 47 of the conduit rotates about its own axis while the flushing ring 60 remains stationary. The intermediate vertical portion of the conduit travels in a circular path or orbit; that is to say, it and the inclined conduit sections above and below revolve about the centre of the plate 32. As the plate rotates, it carries with it the pinion 87 meshing with the stationary internal gear 86, so that the pinion is rotated and transmits motion to the worm shaft 89 from which the cams 95 and 96 are driven. Rotation of the cams causes oscillation of the arm 98 so that the rack 97 thereon rotates the pinion 69 alternately in opposite directions through approximately 180°. The pinion 69 which is fixed to the lower vertical conduit section 49 produces similar partial rotation of this section of the conduit, with the result that the lower inclined section swings through an arc of approximately 180°, the swinging taking place simultaneously with the revolution of the conduit. As the vertical conduit section 49 rotates about its own axis, it carries the pinion 102 along the circularly curved rack, so that the pinion is rotated and rotates the sprocket 103 over which the endless chain 105 runs. Since the conduit section rotates alternately in opposite directions, the chain will be moved alternately in opposite directions and will cause reciprocation of the trough or chute 78 on the inclined section 76, so as to move the delivery point of the cloth in and out on the conduit as it swings and revolves. The relation of the pinion and rack is such that the chute 78 moves out as the conduit swings out to the radial position shown in broken lines, Figure 1, and also in detail in Figure 6, and draws up on the conduit as it swings into position under the plate 32. Owing to the bottom of the conduit section 76 being cut away at its outer end, this movement of the chute shifts the delivery point of the cloth in and out in the length of the conduit section and has the same effect as lengthening or shortening the conduit. In fact, the lower conduit section including the sliding chute member 78 may be regarded as a conduit of changeable length.

The ratio of gearing between the internal gear 86 and the conduit rotating pinion 69

is such that the angular speed of the vertical conduit section 49 about its own axis is much less than the angular speed of the plate 32 about its axis. The result of this speed relation is that the whole conduit will revolve several times while the lower section swings out once from the centre to the circumference of the kier. The result is that the delivery end of the conduit will trace a roughly spiral path from the centre to the wall of the kier. The profiles of the cams 95 and 96 are such that the swing of the conduit lower section is more rapid when it first commences to move away from the kier centre than during the latter part of the swing. This variation in speed causes the path traced to depart somewhat from a true spiral in that the inner turns are spaced farther apart than the outer turns. The profiles of the cams further cause the conduit to swing inwardly at a slightly different speed than during its outward swing, so that it does not exactly retrace its path. Preferably the speed of swing increases toward the centre of the kier.

The roped cloth feeds through the conduit at a lineal speed in excess of the greatest lineal speed of the conduit discharge end and preferably more than twice the lineal speed of the conduit discharge end. The result is that the cloth is laid in the kier not in a single smoothly curved strand but in a mound or ridge under and following exactly the path traced by the conduit discharge end. The plate 32 rotates at constant speed and therefore, disregarding any variation caused by independent movement of the conduit itself, the discharge end of the conduit will travel at higher lineal speed at the wall of the kier than adjacent the centre, due solely to the difference in distance from the centre of revolution. The cloth feeds through the conduit at a uniform lineal speed and it therefore follows that the pile or ridge of cloth deposited will increase in size from the wall toward the centre of the kier. This increase in the size of the cloth pile toward the centre is compensated for by the variable speed of swing of the conduit to space the turns of its path farther apart toward the centre of the kier. When a layer of cloth has been deposited in the kier, it has the appearance of being somewhat higher at the centre and the spiral mound is more clearly defined. When, however, succeeding layers are deposited, the weight flattens out the higher mounding toward the centre of the kier, this flattening being possible on account of the greater spacing in the turns of the spiral, providing room into which the piled-up cloth may flow, in the radial direction of the kier. Near the wall of the kier where the pile or mound is low, the turns of the spiral are closely arranged and there is sub-

stantially no space for radial movement of the cloth when under pressure. The net result is that each layer of cloth, while irregular in thickness when first deposited, virtually resolves itself into a layer of uniform thickness. As already stated, the conduit is so arranged that it never piles exactly at the centre of the kier and in this way any piling-up in the centre of the kier is definitely prevented, so that the cloth piles level from the bottom to top of the kier.

When the kier has been piled as full as possible without obstructing the movement of the conduit, the motor is stopped, the cloth rope severed and the end allowed to slip through the piler, the flushing ring 60 lifted off the upper end of the conduit and the piling mechanism raised from the kier to permit sealing thereof. Before stopping the motor, the operator ascertains that the conduit is swung to its inner position where it will not catch on the shoulder of the kier during removal. The position of the conduit is indicated by the gong 112, which rings every time the conduit is swung fully under the machine.

While the preferred embodiment of the invention has been described and illustrated, it must be understood that the invention is not confined to the details of construction, as numerous variations may be made without departing from the spirit of the invention; for example, the internal gear 86, the teeth of which are parallel with the vertical axis of the machine, may be replaced by a gear with teeth cut radially of the machine, in which case the pinion 87 will be disposed in a vertical plane and may be connected directly to the shaft 89, thus eliminating the mitre gears 88. It will also be understood that by changing the gear ratios, the discharge end of the conduit may be caused to travel in a path other than the spiral path described.

Having thus described my invention, what I claim is:

1. In a cloth piling machine, a support, a conduit carried thereby including a section rotatable in the support, and a second section above the first fixed relatively to the support and inclined, lugs on the lower end of the inclined section on opposite sides of the vertical plane thereof connected to the support, and a brace disposed in the vertical plane of the section and inclined oppositely to the section and connected between the upper end of the section and the support, whereby the second section is rigidly connected to the support and the rotatable section relieved of the weight thereof and means to rotate the rotatable section.

2. In a cloth piling machine, a support, a conduit carried thereby including a section rotatable in the support, and a second section above the first fixed relatively to the

support and inclined, lugs on the lower end of the inclined section on opposite sides of the vertical plane thereof connected to the support, a post projecting upwardly from the plate in the vertical plane of the inclined conduit section, a clevis thereon, an adjustable telescopic brace pivotally connected at its upper end to the upper end of the inclined conduit section, and inclined oppositely to the inclined conduit section and pivotally connected at its lower end to the clevis and adjustable axially in the socket whereby the inclined section is rigidly connected to the support and the rotatable section relieved of the weight of the inclined section and means to rotate the rotatable section.

3. In a cloth piling machine, a rotatable support, a conduit carried thereby including a section rotatable in the support eccentric thereto, a second section extending from the first section to a point in the axial line of the support above the support, and a three-point connection between the second section and the support to relieve the rotatable section of the weight of the second section and to maintain the second section rigid with respect to the support and with its upper end centered in the axial line of the support and means to rotate the rotatable section.

4. In a cloth piling machine, a support, a conduit carried thereby including a section rotatably mounted in the support, and a second section inclined relatively to the first and rigidly connected thereto, means to rotate the rotatable section, a post carried by the support, and a steady pin axially in line with the rotatable section revolvably connected between the same and the post at a point remote from the support to hold the rotatable section in position for free rotation notwithstanding the side draft of the inclined section.

5. In a cloth piling machine, a support, a conduit carried thereby including a section rotatably mounted in the support and depending therefrom, a second section inclined relatively to the first and rigidly connected thereto, means to rotate the rotatable section, a post depending from the support, an arm adjustable on the post and a steady pin carried by the arm coaxially with the rotatable conduit section and engaging said conduit section at substantially its lower end to support the section against movement from its proper position by inclined section such as would interfere with the free rotation thereof.

6. In a cloth piling machine, a support, a conduit carried thereby including a central section passing through the support and rotatable therein, and upper and lower sections inclined to the central section, means to rotate the central section, a three-point connection between the upper section and support to rigidly support the upper section

independently of the central section and connection between the support and central section at the junction of the lower inclined section to resist lateral thrust due to weight of the lower section and maintain the central section in predetermined relation with the support. 70

7. In a cloth piling machine, a conduit including a rotatable section and a relatively inclined section fixed thereto for oscillation, and means for rotating the rotatable section alternately in opposite directions comprising a pinion on the rotatable section, an arcuate rack meshing with the pinion, a pair of cams, and an oscillatable pivotally mounted arm connected with the rack engaging between the cams and by which the rack is moved, and means for rotating the cams. 75

8. In a cloth piling machine, a conduit including a rotatable section and a relatively inclined section fixed thereto for oscillation, and means for rotating the rotatable section alternately in opposite directions comprising a pinion on the rotatable section, a circularly curved rack meshing with the pinion, a pivoted arm carrying the rack, a pair of cams, means on the arm engaging between the cams for moving and positively controlling motion of the arm and rack, a rotatable support for the conduit and rotating means therefor, a stationary gear, a pinion on the support meshing with said gear, gear connection between said pinion and the cams, and means for rotating the support. 85 90 95 100

9. In a cloth piling machine, a conduit including a rotatable section and a relatively inclined section fixed thereto for oscillation, and means for rotating the rotatable section alternately in opposite directions comprising a pinion on the rotatable section, an arcuate rack meshing with the pinion, a pair of cams, and an oscillatable pivotally mounted arm connected with the rack engaging between the cams and by which the rack is moved, a rotatable support for the conduit and rotating gear, a stationary gear, a pinion on the support meshing with said gear, a shaft driven by the pinion, worms on said shaft, worm wheels connected to the cams 105 110 115 and meshing with said worms, and means for rotating the support.

10. In a cloth piling machine, a frame, a cloth conduit rotatably mounted within the frame and adapted to oscillate from a position under the frame and permitting movement through the mouth of a kier or the like to an extended position not permitting such movement, means to oscillate the conduit, and a conduit position indicator comprising a cam rotatable by the conduit oscillating means, a member engaging the cam and an alarm device to be operated by said member when the conduit is positioned under the frame. 120 125 130

11. In a cloth piling machine, a support, a conduit section rotatably mounted therein comprising a pair of telescopically arranged members, rotating means connected to one of said members, a further conduit section rigidly connected to the other of said members and extending radially therefrom, one of said members being recessed, and means on the other member engageable in said recess to hold the members against independent rotation and to predetermine the relation of the rotating means and radially extending section.

12. In a cloth piling machine, a support, a conduit section rotatable therein comprising a pair of telescopically arranged members, the outer of which includes a chuck to hold the inner member, means for rotating the section, an upper nonrotatable conduit section entering the first section, means for independently supporting the sections on said support, a lower section rigidly connected to and extending radially from the inner member, and means to hold the members against independent rotation and to predetermine the relation of the rotating means and radially extending section.

13. In a cloth piling machine, a rotatable support, a conduit carried thereby including a vertical section rotatably passing through the support eccentrically thereof, a collar releasably secured to the upper end of the rotatable section and passing through the support and a bearing for said collar secured to the support to suspend the vertical section and permit downward removal thereof from the collar.

14. In combination with a device according to claim 13, means on the support engaging the collar to rotate the rotatable section, a second conduit section extending laterally from the rotatable section and interengaging means on the rotatable section and collar to hold the two against independent rotation and to compel assembly of the laterally extending section in predetermined relation to the rotating means.

15. In a cloth piling machine, a rotatable support, a conduit carried thereby including a rotatable section passing eccentrically through the support, and suspended by its upper end from the support, a circularly curved rack secured close to the under side of the support concentric with the rotatable conduit section, a bracket on the conduit section adjacent the upper end thereof, a pinion carried by the bracket meshing with said rack, a telescopic conduit section rigidly secured to and extending laterally from the lower end of the rotatable section, means for varying the length of the telescopic section operatively connected to pinion, and means operative by rotation of the support for rotating the rotatable conduit section and means engaging the lower end of the ro-

tatable section and supporting the same against flexion by varying load conditions arising from variation in the length of the telescopic section.

16. In a cloth piling machine, a shallow annular frame, a plate rotatably mounted in the lower end of the frame, an internal gear in the upper end of the frame, a conduit carried by the plate including a rotatable section disposed eccentrically of the plate and suspended at its upper end at substantially the level of the plate, and rotating means for the conduit section located between the upper and lower ends of the frame and including a cam gear driven from said rack, a pivoted rack connected for oscillation by said cam, and a pinion on the conduit section meshing with said pivoted rack.

17. In a cloth piling machine, a conduit including a rotatable section, a pinion encircling the rotatable section, an arm pivoted at one end, a circularly curved rack at the free end of said arm meshing with the conduit pinion, a roller carried intermediate the ends of the arm, a pair of cams engaging the roller from opposite sides and each formed to maintain contact with the roller at all times, said cams being further formed to oscillate the arm at an angular speed decreasing from one end of its swing to the other, and vice versa, and means to rotate the cams.

18. In a cloth piling machine, a conduit including a rotatable section, a pinion encircling the rotatable section, an arm pivoted at one end, a circularly curved rack at the free end of said arm meshing with the conduit pinion, a roller carried intermediate the ends of the arm, a pair of cams engaging the roller from opposite sides and each formed to maintain contact with the roller at all times, said cams being further formed to oscillate the arm at an angular speed decreasing from one end of its swing to the other, and vice versa, a rotatable support for all parts aforesaid in which the rotatable conduit section is eccentrically disposed, a stationary rack surrounding the support, means to rotate the support, and gear connection between the rack and cams for rotation of the latter upon rotation of the support.

19. In a cloth piling machine, a support, a cloth conduit carried thereby including an oscillatable lower portion, a rigid extension of said conduit portion in alignment with the upper surface thereof, a slidable extension of said conduit portion, running wheels supporting the slidable extension on the upper surface of the conduit portion and on the rigid extension thereof, and means to move the slidable extension in and out on said conduit portion as it oscillates.

20. In a cloth piling machine, a support, a cloth conduit carried thereby including a

part rotatable in the support and an inclined part carried by the rotatable part for oscillation thereby, a rigid extension of said inclined conduit portion in alignment with the upper surface thereof, a slidable extension of said inclined conduit portion, running wheels supporting the slidable extension on the upper surface of the inclined conduit portion and on the rigid extension thereof, and means to move the slidable extension in and out on the inclined conduit portion as it oscillates, including a curved rack on the support concentric with the rotatable conduit portion, a pinion carried by the rotatable conduit portion and meshing with said rack, a sprocket connected to the pinion, a sprocket at the end of the rigid conduit extension, an endless chain passing

over said sprockets and connected to the slidable conduit extension, and means to rotate the rotatable conduit portion alternately in opposite directions, comprising a rack encircling the support, a pinion on the support meshing with said encircling rack, a pinion on the rotatable conduit portion, a lever pivoted on the support, an arcuate rack carried by the lever meshing with the conduit pinion, a pair of cams rotatably mounted on the support, a roller on the lever engaged between said cams, driving connection between the support pinion and said cams and means to rotate the support.

In witness whereof, I have hereunto set my hand.

JOHN J. LYTH.
